Primary Examiner — Michael C Stout*Assistant Examiner* — Fitzgerald L Butac(74) *Attorney, Agent, or Firm* — Demian K. Jackson; Jackson IPG PLLC(57) **CLAIM**

The ornamental design for a radiating fin, as shown and described.

DESCRIPTION

FIG. 1 is a perspective view of a radiating fin showing my design; and,

FIG. 2 is a front view thereof.

A left view, a right view, a top view and a bottom view of the radiating fin are omitted because the radiating fin is very thin and no design features are shown.
